Attorney

UNITED STATES PATENT OFFICE.

FRED IVAN GREEN, OF TORONTO, ONTARIO, CANADA.

LIGHTING-FIXTURE.

1,357,634.

Specification of Letters Patent.

Patented Nov. 2, 1920.

Application filed November 1, 1919. Serial No. 335,026.

To all whom it may concern:

Be it known that I, FRED IVAN GREEN, a subject of the King of Great Britain, of the city of Toronto, county of York, Province 5 of Ontario, Canada, have invented certain new and useful Improvements in Lighting-Fixtures, of which the following is a specification.

My invention relates to improvements in 10 lighting fixtures, and one object thereof is to provide a device of the class described whereby a fixture may be readily mounted for use, and demounted, without in any manner interfering with the permanent wiring in the walls or ceiling, and thus prevent 15 damaging of the walls and ceiling, and the wiring therein, very commonly now caused during these operations. Another object of my invention is to utilize a canopy or equivalent element as a coupling means whereby 20 the weight of the electric fixture supported thereby is ultimately carried by a suitable support carried by the wall or ceiling, and without the necessity of having to use fastening means to couple the canopy to its 25 support which would in any manner deface the walls or ceiling, thereby permitting the said canopy to be readily placed and replaced when the fixture is mounted or demounted. An embodiment within my 30 invention, and modifications thereof will be hereinafter more particularly set forth, and what I claim as new will be pointed out in the claims forming part of this specification.

Figure 1 is a side elevation of the major portion of my fixture attached to portion of a wall or ceiling shown in section; the canopy and a coupling for the fixture being shown in vertical central section; Fig. 2 is 35 an elevation of the outer end of the plug receptacle; Fig. 3 is a vertical cross section on the line 3—3, Fig. 2 with the canopy attached to the plug receptacle; Fig. 4 is a side elevation of the major portion of my fixture housed within an outlet box, which is 40 attached to portion of a wall shown in section, a modified form of canopy and coupling for the fixture being shown in vertical central section, and Fig. 5 is a part side elevation of a modified form of plug receptacle, showing the same mounted in an outlet box, shown in section, which is carried by portion 45 of a wall or ceiling, a modified form of canopy being also partly shown in section 50 and adapted to be coupled directly to said wall-box.

In the drawings, like characters of reference refer to the same parts.

A certain essential element of my lighting fixture, known as the plug receptacle or conduit outlet, that is the receptacle which receives the plug wired to the electric fixture, when once placed in position, becomes a permanent fixture.

From the following specification, it will 65 be understood that my preferred form of plug receptacle or conduit outlet may be used without an outlet box, though in the broad conception of my invention any suitable type of plug receptacle or conduit outlet 70 may be used, and the same may be, if desired, mounted within any suitable type of wall-box.

In the majority of lighting fixtures or fixture canopies with which I am acquainted, 75 the canopy itself is either directly attached to the wall or ceiling, or permanently forms part of a conduit outlet that is directly attached to the wall or ceiling, and in all such cases, such attaching means necessarily injures the wall or ceiling, particularly when the said canopies have to be removed.

Obviously, since my canopy is not coupled by such a class of fastening means to the wall or ceiling, it can be readily uncoupled 85 from its supporting element without in any wise damaging the wall or ceiling; this is a great advantage, not only when a tenant moves from one house to another, but also for purposes of inspection.

All the essential parts of my fixture will be standardized so that the canopy associated with the lighting fixture can be readily coupled to the permanent conduit outlet carried by the wall or ceiling, and as the plug 95 permanently wired to the lighting fixture will also be of standard size, the same can be readily inserted into, and removed from, the socket carried by said conduit outlet.

A is a preferred form of conduit outlet, 100 and the same is made of suitable refractory material. This conduit outlet is coupled to the wall or ceiling B by any suitable means such as screws C passing therethrough, in the manner well-known in electrical art. 105 The said conduit outlet is designed to be permanently attached to the wall or ceiling, and it may be wired after any suitable manner; for this purpose I preferably provide the conduit outlet A with two holes D 110 and E formed therein, and passed down through these holes are wires F and G.

The wire F is passed through the inner end of the hole D and around a binding screw H and pinched between the head of this screw and the flange I of the socket J. A threaded nut 2 is embedded in the conduit outlet A underneath portion of the flange I so as to receive the screw H. The wire G is passed through a slot 3 formed in a metal plate 4, and is pinched between the head of the screw 5 (which screws through the plate 4) and the said plate. The plate 4 is positioned as shown in Figs. 2 and 3 by means of a slot 6 formed in the conduit outlet A, and after this plate has been positioned the said slot may be closed by any suitable cement.

To permit the placing of the screw 5, the outer end of the conduit outlet A is recessed as shown at 7.

Passing through portion of the flange I and through the flanges 8 carried by the socket J, are any suitable fastening means well known in the art, for instance screws 9 which pass through holes 10 (see dotted lines Fig. 3) formed in the conduit outlet A, and screw into nuts 11 mounted within pockets 12 formed in said conduit outlet, and which pockets are afterward sealed.

13 is any suitable type of plug, and the same is supported by a socket J in any suitable manner, though the preferred manner of mounting the said plug in the said socket is as shown by means of the screw threads; but it must be understood that I have not confined myself to using this form of coupling.

The plug 13 is provided with any suitable contact plate 14, which makes contact with the screw 5 when said plug is fully coupled to the socket J. 15 and 16 are the wires permanently carried by the plug 13, and these wires are passed through, or otherwise associated with, the pipe 17 of the electric light fixture.

45 The path of the current will be understood by one skilled in the art as there is nothing particularly novel in the manner in which the electrical connections are made.

The preferred form of conduit outlet A is provided exteriorly with a thread a, and engaging with this thread is a thread b of the canopy 18. The lower portion of the canopy is reinforced as shown at 19, and this reinforcement is threaded so that the threaded portion of the pipe 17 of the electric light fixture may be coupled thereto.

In order to couple the electric light fixture to the conduit outlet A, since there is sufficient wire between the plug 13 and the pipe 17, it will be understood that this plug may be grasped by the hand and screwed into the socket J, and then the canopy 18 will be screwed on to the conduit outlet A so that the weight of the electric fixture 65 will be carried by the said canopy and con-

duit outlet, and of course ultimately by the wall or ceiling.

In Fig. 4, the conduit outlet A is shown as mounted in a wall-box 20, and the canopy 18' is shown as having threaded engagement with said conduit outlet A. In order to cover the opening between the wall-box and the canopy 18', a truncated ring 21 is slipped on said canopy and rests against the annular flange 22 thereof, and when 75 this canopy is screwed home, the said truncated ring contacts with the wall or ceiling B and so hides the wall-box.

In this figure I show a modified form of coupler for coupling the pipe 17 of the electric light fixture to the canopy 18', so that the canopy may be turned independently of said pipe 17. 23 is an internally-threaded bushing having a flared head 24, which is within said canopy and rests against the lower end thereof. The outer face of the bushing 23 is threaded and receives a jam nut 25. Of course the pipe 17 screws into the bushing 23, and by retracting the nut 25, the canopy 18' may be independently 90 turned. Jamming the nut 25 against the canopy 18' locks the same against turning.

In Fig. 5 I show a wall-box 26 as performing one of the functions of the conduit outlet A. The inner wall of this wall-box 95 is provided with a thread 27 with which engages the thread b' of the canopy 18''. It will of course be understood without further description that the electric light fixture is carried by this canopy. The plug 100 13 is of course coupled to the socket J, and this socket is suitably carried by the plug receptacle A' with which electrical connections are made. In this form of my invention, the receptacle A'' has no thread. 105

It will be observed that the canopies 18 and 18' house the more or less slack of the wiring. Obviously, very little slack need be used with the form illustrated in Fig. 4, because the canopy 18' can be slid down the pipe 17 to permit the hand to readily grasp the plug 13 to engage the same with the socket J, and then afterward the canopy can be moved up into place and screwed over the conduit outlet A after which operation the 115 jam nut 25 can be placed and screwed home.

The conduit outlet permanently carried by the wall or ceiling may consist of one part only such as the conduit outlet A shown in Fig. 1, or it may consist of two parts 120 (a) the outlet or wall boxes 20 and 26, and (b) the conduit outlet A housed therein.

Although I state it is an object of my invention to support the fixture by means (for example the canopy 18) not attached 125 to the wall or ceiling by attaching means that would deface the same, still I may use such means common in the art, such as screws or nails to attach the various suitable forms of canopy to the wall or ceiling 130

where the plug 13 is coupled to the pipe 17 of the fixture by sufficient "slack" to permit said plug to be coupled to, or uncoupled from, its associated socket, and where said pipe 17 is coupled to said canopy 18 or equivalent element, to be within the claims of my invention.

The said "slack" in the wire is a very important feature of my invention in combination with the plug 13 and its associated parts specifically conceived, and any means to detachably attach the canopy 18 or equivalent element directly or indirectly to the wall or ceiling.

5 While I have described what I consider to be the best embodiments of my invention, it must be understood that the principle may be embodied in still other forms and I desire not to be limited beyond the requirements of the prior art and the terms of my claims.

What I claim is,

1. A lighting fixture comprising a conduit outlet permanently carried by a wall or ceiling; a socket carried thereby and adapted for electrical connections therewith; a fixture pipe; wires passing therethrough; a plug adapted for electrical connection with said wires and spaced apart from said pipe by said wiring which provides the required slack, and designed to be detachably coupled to said socket, and a coupling element

in the form of a canopy through which said pipe opens and to which the same is coupled, adapted to removably couple said pipe and fixtures carried thereby directly to said conduit outlet.

2. A lighting fixture comprising an outlet member permanently carried by a wall or ceiling; an electric coupling element carried thereby and adapted for electrical connections; an electric coupling element removably associated with said first-mentioned coupling element; an electric fixture wired to said second-mentioned coupling element so as to provide for the necessary slackness in the wiring as set forth, and a canopy adapted to carry said fixture, and to be removably coupled to any suitable support.

3. A lighting fixture comprising an outlet member permanently carried by a wall or ceiling, and provided with an external thread; an electric coupling element carried thereby and adapted for electrical connections; a canopy adapted to have threaded engagement with said outlet member and aperture to permit of electrical connections being made with said outlet member, and means associated with said canopy whereby the weight of a fixture electrically connected with said outlet member may be carried by said canopy.

FRED IVAN GREEN.
